TOY OR MINIATURE BED

Chester T. Martin, McColl, S. C.

Application February 24, 1949, Serial No. 78,151

9 Claims. (Cl. 5—178)

1

My invention relates to a toy or miniature bed.

An important object of the invention is to provide a collapsible miniature bed, which may be distended or collapsed without the aid of tools or implements.

A further object of the invention is to provide a bed of the above-mentioned character the head and foot members of which engage stops, carried by the body portion or rails, to thereby limit the outward movement of such members, their inward movement being prevented by removable sides which are received in grooves formed in the head and foot members.

A further object is to vertically taper at least one end of each side, thereby providing points of contact only at the top of each side, between the side and the head and foot members, leaving the sides free to be inserted into and removed from positions within the grooves.

A further object of the invention is to provide a simplified pivotal connection between the rails or bottom members and the head and foot members, so that there is no liability of the pivot elements working loose.

A still further object of the invention is to provide a miniature bed which is simple in construction, inexpensive to manufacture, and which will occupy a minimum space during shipment.

Other objects and advantages of the invention will be apparent during the course of the following description.

In the accompanying drawings, forming a part of this application, and in which like numerals are employed to designate like parts throughout the same,

Figure 1 is a plan view of the miniature bed,

Figure 2 is a vertical longitudinal section taken on line 2—2 of Figure 1,

Figure 3 is a transverse vertical section taken on line 3—3 of Figure 1,

Figure 4 is an enlarged fragmentary vertical section taken on line 4—4 of Figure 1,

Figure 5 is an enlarged fragmentary vertical section taken on line 5—5 of Figure 1,

Figure 6 is an enlarged fragmentary vertical section taken on line 6—6 of Figure 1, part broken away,

Figure 7 is a view similar to Figure 2, showing the bed in the folded or collapsed position,

Figure 8 is a transverse fragmentary sectional view showing a modified form of pivotal connection between the bed bottom and head and foot members,

Figure 9 is an enlarged fragmentary horizontal

2

section showing a further modification in the pivotal connection, and,

Figure 10 is an enlarged fragmentary horizontal section showing a still further modification of the pivotal connection.

In the drawings, where for the purpose of illustration are shown preferred embodiments of my invention, attention is called first to Figures 1 to 7 inclusive, wherein the numeral 10 designates a bed bottom, preferably formed of plywood, and this bed bottom is rigidly secured to longitudinal side rails 11 by nails, glue, or the like. Arranged beneath the rails 11 at their opposite ends are triangular stop-blocks 12, rigidly secured to the rails by any suitable means, such as nails, glue, or the like. The tops of the rails 11 are preferably slightly rounded as at 13, while the ends 14 are perpendicular and are in alignment with the perpendicular faces 15 of the blocks 12.

The numerals 16 and 17 designate head and foot members which are substantially identical. Each head and foot member includes vertical posts 18, provided upon their inner sides with grooves 19 to receive vertical edges of a panel 20, held therein by glue, or the like. These posts 18 extend downwardly beyond the lower edge of panel 20 forming legs 21. The grooves 19 preferably are cut through the opposite ends of each post 18. The posts are provided between their ends with enlargements 22, projecting longitudinally of the bed, and these enlargements have tapered ends 23 which blend into the upper and lower ends of the posts. The enlargements 22 have longitudinal vertical grooves 24 cut therein, and extending through their upper and lower tapered ends 23.

Means are provided to pivotally connect each post 18 with the adjacent end of the rail 11. This means comprises a transverse pivot element in the form of a bolt 25, which extends through a transverse opening 26 formed in the post 18. The bolt 25 has an outer head 27 which is slotted for engagement with a screw driver. The bolt receives thereon a nut 28, mounted within a square recess 29 formed in the inner face of the post 18. The bolt 25 extends inwardly beyond the nut 28, and is pivotally mounted within a transverse opening 30 formed in the adjacent rail 11. The bolt is clamped to the post 18 and does not turn with respect to the post, but is freely turnable within the opening 30 in the rail. The bolt 25 has a sliding fit within the opening 30 and has no screw-threaded engagement therewith. The distance between the cen-

ter of the bolt and the adjacent outer end of the rail 11 is equal to the distance between the inner side of the groove 19 of the post or the inner face of the panel 20 and the center of the bolt. This results in the panel 20 being arranged perpendicularly when the head or foot member 16 or 17 is opened, and such panel will then contact the perpendicular face of the stop-block 12. When the head and foot members 16 and 17 are moved to their opened perpendicular positions, they are retained in these positions by sides 31, the opposite ends 32 and 33 of which are inserted within the vertical grooves 24. These grooves 24 have their lower ends open, as stated, and the downward movement of each side is limited by stops in the form of dowels 34, inserted within openings formed in the posts 18 at the bottoms of the grooves. The end 33 of each side 31 is vertically inclined or beveled, extending inwardly downwardly, whereby the top of the side 31 has a greater length than its bottom, see Figure 6. This construction provides contact points 35 for each side 31, which remain in permanent contact with the head or foot members 16 or 17 when the bed is assembled. These points of contact rigidly hold the head and foot members 16 and 17 against inward swinging movement, while their outward swinging movement is prevented by the panels 20 contacting with the stop-blocks 12. The advantage gained in providing the beveled ends 33 and the upper contact points 35 is that the sides 31 may be readily inserted and removed, without binding, and as soon as the contact points 35 are lifted above the grooves 24, the sides 31 will freely pass out of the grooves 24. Likewise, the beveled or tapered ends 33 facilitate the insertion of the sides 31 into the grooves.

Attention is directed next to Figure 9, wherein I have shown a modified manner of pivotally connecting each post 18 with the adjacent end of each rail 11. In Figure 9, the numeral 36 designates a square recess provided in the outer face of each rail 11, for receiving a nut 37, to hold the same against turning. Aligned openings 38 and 39 are formed in the post 18 and rail 11, respectively, for receiving a bolt 40 inserted from the outer side of the post 18, as shown. A second nut 41 is provided at the inner side of the rail 11, and mounted upon the bolt 40. With this arrangement, the bolt 40 is held against turning movement with respect to the rail 11, but is turnable within the opening 38. All other points are identical with the corresponding points shown and described in connection with the first form of the invention.

In Figure 10 a further modified form of pivotal connection between each rail 11 and each post 18 is shown. In Figure 10 aligned openings 42 and 43 are formed in the post 18 and rail 11 respectively, and these aligned openings receive a metal sleeve 44 which is freely turnable therein. The sleeve 44 extends slightly beyond the outer side of the post 18 and the inner side of rail 11, as shown, and receives a bolt 45 carrying washers 46 at its opposite ends, and a nut 47 at its inner end adjacent to the inner side of rail 11. All other parts of the miniature bed are identical with those shown and described in connection with the first form of the invention.

In Figure 8 I have shown a still further modification of the pivotal connection between the rails 11 and posts 18. In Figure 8 the numeral 48 designates a transverse rod or pin which extends through openings 49 in the rails 11 and has its

opposite ends rigidly secured within aligned openings 50 in the posts 18. The rails 11 are freely turnable with respect to the rod 48, the ends of which have a forced fit in the openings 50. All other parts of the miniature bed are identical with those shown and described in the first form of the invention.

It should be noted with respect to the first form of the invention, as shown clearly in Figure 7, that the distance between the centers of the bolts 25 and the top surface of the bed bottom 10 is slightly less than the distance between the centers of the bolts and the inner faces of the panels 20. This results in the panels 20 being maintained slightly spaced from the upper face of the bottom 10 except at the extreme inner ends of the panels 20 when the bed is folded or collapsed, Figure 7. This arrangement is advantageous, since it prevents any tendency for the paint on the panels 20 to stick to the paint on the bottom 10 during shipment.

It is to be understood that the forms of the invention herewith shown and described are to be taken as preferred examples of the same, and that various changes in the shape, size and arrangement of parts may be resorted to, without departing from the spirit of the invention or the scope of the subjoined claims.

Having thus described my invention, I claim:

1. A toy or miniature bed, comprising a bottom including side rails having openings disposed near the ends of said side rails, depending stop-blocks secured to the side rails adjacent to their ends and arranged a substantial distance below the openings, head and foot members, each of said members comprising posts and a panel secured to the posts and extending between the same, each post having an opening in alignment with one of the openings in the adjacent side rail, bolts disposed within the openings in the posts and having portions extending through the openings in the side rails for pivotally connecting the head and foot members to the side rails, each post being provided with a longitudinal groove extending a substantial distance above the bolts, and sides extending removably into the grooves of the posts a substantial distance above the bolts, such sides preventing the inward swinging of the upper ends of the head and foot members when the bed is assembled, the stop-blocks engaging the head and foot members below the bolts to limit the outward swinging of the upper ends of said members.

2. A toy or miniature bed, comprising a bottom including side rails having openings near their ends, depending stop-blocks secured to the side rails adjacent to their ends and below the openings and having faces flush with the ends of the rails, head and foot members, each of such members comprising posts and a transverse panel connected with the posts, each post having an opening in alignment with one of the openings in the adjacent side rail, bolts disposed within the openings in the posts and having portions projecting into the openings in the side rails to pivotally connect the head and foot members with the side rails, each post being provided with an enlargement having a groove extending through the same, stops secured to the posts near the lower ends of said grooves, the grooves extending a substantial distance above the bolts, and sides extending removably into the grooves of the posts above the bolts, the sides engaging upon the stops near the lower ends of the grooves, each side having one end inclined inwardly toward its bot-

tom and forming substantially a point contact between the side and the bottom of one of the grooves, the sides preventing the inward swinging of the upper ends of the head and foot members, the ends of the rails and stop-blocks contacting the panels a substantial distance below the bolts to limit the outward swinging of the upper ends of the head and foot members.

3. A toy or miniature bed, comprising a bottom including side rails having openings near their ends, stop-blocks secured to the side rails adjacent to their ends, head and foot members, each of said members comprising posts and a panel connecting the posts, the posts having openings in alignment with the openings in the side rails and recesses formed in their inner surfaces, bolts arranged within the openings of the posts and extending turnably through the openings in the side rails and serving to pivotally connect the posts and side rails, nuts secured to the bolts and arranged within the recesses in the posts and held with the bolts against turning relative to the posts by the recesses, the posts being provided with inwardly facing enlargement having longitudinal grooves extending entirely therethrough, stops mounted upon the posts near the bottoms of the longitudinal grooves, and sides having ends removably extending into the grooves and resting upon the stops near the bottoms of the grooves, the sides preventing inward swinging of the head and foot members while the stop blocks prevent the outward swinging of said members.

4. A toy or miniature bed, comprising a bottom including side rails having openings near their ends, stop-blocks secured to the side rails adjacent to their ends, head and foot members, each of said members comprising posts and a panel connecting the posts, each post having an opening in alignment with one of the openings in the adjacent side rail, a rod secured within the openings of the posts of each member and extending through the adjacent openings in the side rails and serving to pivotally connect the side rails and posts, each post being provided with a longitudinal groove, and sides extending removably into the grooves of the posts, each side having one end inclined inwardly toward its bottom and forming a point contact between the side and the bottom of a groove of the adjacent post, the sides preventing inward swinging of the head and foot members, the stop-blocks engaging the panels to limit the outward swinging of the head and foot members.

5. A toy or miniature bed, comprising a bottom including side rails, said side rails having transverse openings near their ends and recesses upon their outer faces leading into the openings, head and foot members, each member comprising posts, the posts of each member provided with longitudinal grooves upon their inner edges and having transverse openings, bolts passing through the transverse openings of the posts and the transverse openings of the rails, an inner nut carried by each bolt and arranged within the recess of the rail, a second nut carried by each bolt and engaging the inner face of the rail, and sides having ends removably extending into the longitudinal grooves.

6. A toy or miniature bed, comprising a bottom including side rails having transverse openings near their ends, stop-blocks secured to the side rails adjacent to their ends, head and foot members, each member comprising posts, the posts of each member having longitudinal grooves upon their inner edges and transverse openings, a

5 sleeve arranged within each transverse opening of the post and extending into the adjacent transverse opening of the rail, a bolt arranged within each sleeve and having a stop element at its outer end, a nut carried by the inner end of each bolt, and sides having ends removably extending into the grooves.

7. A foldable miniature bed comprising a bottom including longitudinal side rails, depending 10 stop-blocks secured to the side rails adjacent to their ends and above the stop-blocks with transverse openings, head and foot members arranged adjacent to the ends of the bottom, each of said 15 members including a transverse panel and a pair of posts secured to the panel and disposed upon the outer sides of the side rails, the posts of each pair overlapping end portions of the side rails, the posts being provided above their lower 20 ends with transverse openings arranged in alignment with the adjacent openings of the side rails, bolt means extending through the transverse openings of the posts and side rails and pivotally connecting the head and foot members with the bottom and supporting the bottom in an elevated position, the transverse panels of the head and foot members being arranged beyond the adjacent ends of the side rails and extending below the side rails and engaging the depending 25 stop-blocks to limit upward outward swinging movement of the upper ends of the head and foot members, the posts of the head and foot members being provided upon their inner faces with longitudinal grooves having stop means at 30 their lower ends near the elevation of the bolt means, the grooves extending for substantial distances above the bolt means and having their upper ends open, and longitudinal sides extending between the head and foot members and having ends removably extending into the grooves 35 and resting upon the stop means and holding the upper ends of the head and foot members against swinging downwardly, said sides extending above the bolt means for a substantial distance.

8. A foldable miniature bed comprising a bottom including longitudinal side rails provided 40 near their ends with transverse openings, head and foot members arranged adjacent to the ends 45 of the side rails, each member including a transverse panel arranged beyond the adjacent ends of the side rails and posts secured to the ends of the panel and disposed upon the outer sides of the side rails, the posts having transverse 50 openings above their lower ends and arranged in alignment with the openings of the side rails, the posts having recesses in their inner faces adjacent to the side rails and leading into their 55 transverse openings, bolts engaging in the openings of the posts and extending turnably into the openings of the side rails for pivotally connecting the posts and side rails, nuts mounted upon the bolts and engaging within the recesses of the 60 posts for holding the nuts and bolts against turning relative to the posts, the panels of the head and foot members extending below the side rails and engaging the ends of the side rails to maintain the head and foot members in upright positions, the posts of the head and foot members being provided upon their inner faces with longitudinal 65 grooves extending for a substantial distance above the bolts, and longitudinal sides extending between the head and foot members and having ends removably extending into the 70 75

grooves and serving to maintain the head and foot members upright.

9. A foldable miniature bed comprising a bottom including side rails having openings, stop-blocks secured to the side rails adjacent to their ends, head and foot members, each of said members comprising posts and a panel connecting the posts, the posts having openings in alignment with the openings of the side rails and recesses formed in their inner faces, bolts arranged within the openings of the posts and extending turnably through the openings in the side rails and serving to pivotally connect the posts and side rails, nuts secured to the bolts and arranged within the recesses of the posts and held with the bolts against turning relative to the posts by the recesses, the posts being provided upon their inner faces with longitudinal grooves extending above the bolts, and sides extending between the head and foot members and having ends removably extending into the grooves and holding the upper ends of the head and foot members against downward swinging movement, the stop-

5

10

15

20

blocks engaging the panels to limit the upward and outward swinging movement of the upper ends of the head and foot members.
